UNITED STATES PATENT OFFICE.

ARTHUR ROBINSON, OF MINNEAPOLIS, MINNESOTA.

FIGURE PROJECTING TOY.

Application filed March 8, 1926. Serial No. 93,051.

My invention has for its object to provide an extremely interesting and fascinating toy which, as illustrated, comprises a figure representing a rearing bronco and a second figure representing a cowboy with mechanism for imparting movements to the bronco and throwing the cowboy through the air to cause him to make a complete somersault and, when correctly thrown, to light astride 10 the bronco.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a plan view of the improved toy; Fig. 2 is a view partly in side elevation and partly in longitudinal central section, taken on the line 2—2 of Fig. 1, with some parts shown in different positions by means of broken lines;

Fig. 3 is a view corresponding to Fig. 2, but showing the movable parts shown in different positions;

Fig. 4 is a view partly in front elevation and partly in transverse vertical section, taken on the line 4—4 of Fig. 3; and

Fig. 5 is a rear elevation of the figure shown in Fig. 4.

The improved toy includes two figures 6 and 7 one of which has the outline of a rearing horse and the other of which has an outline of a man or boy with his legs spread. Preferably each figure 6 and 7 is cut from a single sheet of fibre to prevent the same from warping or being broken. A lithograph sheet 8 is secured to each side of the figure 6 and represents a rearing bronco having thereon the regulation western bridle 9 and saddle 10. The figure 7 has secured to the front and back thereof colored lithograph sheets 11 that represent a cowboy clothed in the regulation wearing apparel. Weighted feet 12, of lead or other heavy material, are secured to the legs of the figure 7.

The figure 6 is mounted on a platform 13 for rocking movement in a vertical plane longitudinally thereof by having the rear feet of the horse integrally formed with a block 14 inserted between the prongs of the bifurcated front end of said platform and secured thereto by a pivot 15. The figure 7

is separate from the rest of the toy, and to throw said figure and cause the same to light astride the saddle 9 on the figure 6, I provide a normally upright throwing lever 16, 60 the lower end of which is inserted between the prongs of the bifurcated rear end of the platform 13 and pivoted thereto at 17. The platform 13 is supported in a raised position on end blocks 18. A coiled spring 19, 65 anchored to the inner face of the rear block 18 and attached to the throwing lever 16 below its pivot 17, normally holds said lever with freedom for rearward swinging movement, until stopped by said block in a horizontal position in the same vertical plane as the rocking movement of the figure 6.

To impart substantially like movements to the figures 6 and 7, the following connections are provided, to wit: a short vertically extended lever 20 is inserted through a longitudinally extended slot in the platform 13 and intermediately pivoted thereto at 21. A link 22 connects the throwing lever 16 above its pivot 17, to the upper end of the lever 20, and a link 23 connects the lower end of said lever 20 to the lower edge of the block 14 and below the pivot 15. Said link 23 is intermediately coiled to form a recoil spring 24. The operating connections 20, 22 and 23 85 are such as to hold the figure in a rearing position when the throwing lever 16 is in normal or upright position, as shown by broken lines in Fig. 2.

To play with the toy, the throwing lever 90 is drawn rearward against the tension of the spring 19 until stopped by the rear end block 18 in a horizontal position, as illustrated by full lines in Fig. 2. This movement of the throwing lever 16 also draws the figure 6 95 into a still further rearing position. The figure 7 is then placed astride the throwing lever 16, as shown by full lines in Fig. 2 and said lever released. When the throwing lever 16 is released, the spring 19 which has been held under tension will swing said lever forward and throw the figure 7 onto the figure 6, as indicated by full lines in Fig. 3, and in which position of the figure 7 the same is astride the saddle 9. The flight of 105 the figure 7 to the figure 6 is indicated by arrows in Fig. 3, and it will be noted that said figure 7 makes a complete somersault.

The purpose of the recoil spring 24 is to prevent a movement of the figure 6, at the 110 time the figure 7 lights thereon, that will throw said figure 7 from the figure 6.

To throw the figure 7 by means of the throwing lever 16 and cause the same to light on the figure 6 astride the saddle 9 requires considerable skill for the reason that the figure 7 must be placed on the throwing lever 16 in a correct longitudinal position thereon in order that the throwing lever actuated by the spring 19 will throw the figure 7 just the right distance. If the figure 7 is placed on the throwing lever 16 too near its pivot 15, said figure will be thrown short of the saddle 9 or if placed on said lever too far away from said pivot, it will be thrown forward of the saddle or over the head of the bronco; or the figure 7 is liable to be thrown on either side of the figure 6. By mounting the figure 6 for movement with the throwing lever 16 and the throwing of the figure 7 on the figure 6, gives the toy the required action, and correctly colored and illustrated lithographs gives the toy a very natural appearance and action in which the cowboy leaps into the air, makes a complete somersault and lights on the saddle on the bronco.

25 The above described toy has in actual usage proven highly entertaining and fascinating.

What I claim is:

1. A toy comprising a relatively flat figure mounted in a vertical plane, a spring-actuated throwing member mounted for movement in said vertical plane, and a loose crotched figure adapted to be supported on said throwing member in a straddled position transversely of the movement thereof and thrown by said member toward the first noted figure, said loose figure when accurately thrown by said member being arranged to light on the first noted figure in a straddled position.

2. A toy comprising a platform, a figure mounted on the platform, a pivoted throwing lever on the platform, a spring operative on said lever and arranged to be placed under tension when said lever is drawn away from said figure, and a loose figure adapted to be supported on said lever in a straddled position when said lever is drawn away from the first noted figure, and thrown toward the first noted figure by said lever when released, said loose figure, when accurately thrown by said lever, being arranged to light on the first noted figure in a straddled position, said loose figure being free for adjustment longitudinally on the throwing lever.

3. A toy comprising a platform, a figure mounted on the platform, a pivoted throwing lever on the platform, a spring operative on said lever and arranged to be placed under tension when said lever is drawn away from said figure, and a loose figure having weighted feet and adapted to be supported on said lever in a straddled position when said lever is drawn away from the first noted figure, and thrown toward the first noted

figure by said lever when released, said loose figure, when accurately thrown by said lever, being arranged to light on the first noted figure in a straddled position.

4. A toy comprising a platform, a figure 70 yieldingly mounted on the platform, a pivoted throwing lever on the platform, a spring operative on said lever and arranged to be placed under tension when said lever is drawn away from said figure, and a loose 75 figure adapted to be supported on said lever in a straddled position when said lever is drawn away from the first noted figure, and thrown toward the first noted figure by said lever when released, said loose figure, when 80 accurately thrown by said lever, being arranged to light on the first noted figure in a straddled position.

5. A toy comprising a platform, a figure 85 and a throwing lever pivotally mounted on the platform, the former in front of the latter, a spring operative on said lever and arranged to be placed under tension when said lever is drawn away from said figure, operating connections from the throwing lever to 90 the figure, and a loose figure adapted to be supported on said lever in a straddled position when said lever is drawn away from the first noted figure and thrown toward the first noted figure by said lever when released, 95 said loose figure, when accurately thrown by said lever, being arranged to light on the first noted figure in a straddled position.

6. The structure defined in claim 5 in which said connection includes a recoil 100 spring.

7. The structure defined in claim 5 in which said connection includes a lever intermediately pivoted to the platform, a link connecting the first noted figure to one end 105 of said intermediately pivoted lever and a second link connecting the other end of said link to the throwing lever.

8. A toy comprising a platform, a figure representing a bronco pivoted to the platform at its rear feet for rocking movement, a throwing lever pivoted to the platform, back of said figure, for swinging movement in the plane of the rocking movement of said figure, an operating connection from said lever to the figure, a spring normally holding said lever in an upright position and arranged to be placed under tension when said lever is moved rearward into a horizontal position, said operating connection being arranged to hold the figure in rearing position when said lever is in an upright position and to move said figure in a still further rearing position when said lever is moved rearward into a horizontal position, and a loose figure representing a cowboy with his legs spread and having weighted feet, said loose figure being adapted to be supported astride said lever, when in a rear horizontal position, and thrown toward the first noted figure.

- ure by said lever when released, said loose figure, when accurately thrown by said lever, being arranged to light on the first noted figure in a straddled position.
- 5 9. The structure defined in claim 1 in which the first noted figure is mounted for rocking movement in said vertical plane.
- 10 10. The structure defined in claim 1 in which said loose figure may be adjusted on said member toward or from the first noted figure.
11. The structure defined in claim 1 in which said loose figure has weights at the outer extremities of its crotch.

In testimony whereof I affix my signature.

ARTHUR ROBINSON.
